UNITED STATES PATENT OFFICE.

BERNARD BRAGER, OF BROOKLYN, NEW YORK.

HAT AND COAT RACK.

1,333,462.

Specification of Letters Patent.

Patented Mar. 9, 1920.

Application filed May 31, 1919. Serial No. 300,943.

To all whom it may concern:

Be it known that I, BERNARD BRAGER, a citizen of Russia, and a resident of the city of New York, borough of Brooklyn, in the 5 county of Kings and State of New York, have invented a new and Improved Hat and Coat Rack, of which the following is a full, clear, and exact description.

This invention relates to hat and coat 10 racks and has particular reference to certain details of construction whereby such devices are rendered more convenient as well as being neater in appearance than similar devices heretofore made.

15 A further object of the invention is to provide a novel form of supporting arm for the accommodation of hats, coats, or other garments, and having special facilities for supporting a mirror.

20 With the foregoing and other objects in view the invention consists in the arrangement and combination of parts hereinafter described and claimed, and while the invention is not restricted to the exact details of 25 construction disclosed or suggested herein, still for the purpose of illustrating a practical embodiment thereof reference is had to the accompanying drawings, in which like reference characters designate the same 30 parts in the several views, and in which—

Figure 1 is a side elevation.

Fig. 2 is a front elevation.

Fig. 3 is a vertical transverse sectional detail on the line 3—3 of Fig. 1; and

35 Fig. 4 is a detail view of one of the socket pieces.

Referring now more specifically to the drawings I show a bracket 10 adapted to be secured flat against a wall or other vertical support by means of screws or the like 40 passing through holes 11. This bracket is made of any suitable design and is provided on its front face with a pair of knuckles 12 having vertical aligned bearing holes.

45 The next main feature of the rack consists of an arm 13 made preferably of a single piece of rod metal bent into two parallel upper and lower members 13^a and 13^b respectively and having therefore a loop or 50 crotch portion 14 at its outer end and oppositely directed journal portions 15 fitted in the aligned holes of the knuckles 12. By virtue of the elasticity of the rod metal from which the arm 13 is made the bearing 55 portions 15 are adapted to be projected upward and downward away from each other

into said holes. Hence this arm is self retained in the knuckles 12 for practical purposes, but may be removed therefrom without disturbing the bracket 10 at any desired time. The crotch portion 14 of the arm is practically straight between the bends merging into the upper and lower portions 13^a and 13^b, but the upper bend is provided with a pair of vertical kerfs 16 on 60 opposite sides thereof.

17 indicates a mirror the frame of which is fitted on its back with a sheet metal clip 18 having a closed top 19, an open bottom 20 and parallel flanges 21. The clip is fixed 70 rigidly to the back of the mirror and constitutes a permanent part thereof. The width of the clip from the back of the mirror to the flanges 21 is practically the same 75 as the diameter of the material from which the arm 13 is made, but irrespective of the precise relative sizes of these parts the flanges 21 are designed to slip snugly downward along the kerfs 16 while the back of the mirror slides close along the front end 80 of the crotch portion of the arm. Again, the space between the flanges is exactly equal to the space between the bottoms of the kerfs and consequently is less than the diameter of the lower portion 13^b of the arm 85 which constitutes a positive stop for the bottom of the clip, while the top of the clip rests upon the upper portion 13^a making a 90 neat and reliable support for the mirror but permitting it to be removed by upward displacement when desired.

Fitted or adjusted along the upper portion 13^a of the arm are any suitable number of socket pieces 22 shown as two in number, one close back of the mirror, and the other 95 farther back toward the wall. As shown in detail in Fig. 4 each of these socket pieces 22 has a horizontal hole 23 through which the arm projects and also is provided with a pair of parallel vertical sockets 24 receiving a like number of horns 25, two for each socket piece. The inner or lower ends of the horns are fitted into the sockets 24 providing for rotation around the vertical axes thereof so that the horns of each pair may 100 lie in the same plane or otherwise for convenience. Obviously these horns constitute hanger members for hats or other garments and if the arm 13 be swung around the axis of the knuckles 12 the horns may likewise 105 be turned around their axes so as to enable 110 the arm to be swung close against the wall

or other support. Furthermore the horns may be lifted out of the sockets if the device is to be taken apart for storage or transportation.

5 I claim:

1. The herein described hat and coat rack comprising a bracket, an arm connected to the bracket and extending outward therefrom, said arm being made of rod metal and having its outer end provided with a pair of vertical kerfs, a mirror having on its back an open bottomed clip with a pair of parallel flanges along its back portion slidably fitted in said kerfs while the movement of the mirror and clip downward is limited by striking against the arm.

10 15 2. In a hat and coat rack, the combina-

tion of a stationary support; an arm connected thereto and projecting outward therefrom, said arm being made of rod metal bent upon itself forming two parallel portions 20 connected by a crotch having a short vertical portion connected to the parallel portions by short bends, the upper bend being provided with a pair of vertical kerfs on its 25 sides, and a mirror detachably supported upon the crotch portion of the arm and having a pair of parallel flanges fitted into said kerfs, while the back portion of the mirror lies snug against the straight portion of the 30 crotch and a portion of the mirror abuts downward against the arm to limit the downward movement thereof.

BERNARD BRAGER.
